UNITED STATES PATENT OFFICE.

SIMEON A. PUGH, OF DADEVILLE, ALABAMA.

HORSE-DETACHER.

SPECIFICATION forming part of Letters Patent No. 376,107, dated January 10, 1888.

Application filed August 3, 1887. Serial No. 246,080. (No model.)

To all whom it may concern:

Be it known that I, SIMEON A. PUGH, a citizen of the United States, residing at Dadeville, in the county of Tallapoosa and State of Alabama, have invented certain new and useful Improvements in Means for Detaching Horses; and I do hereby declare that the following is a full, clear, and exact description of the same, reference being had to the annexed drawings, making a part of this specification, and to the letters and figures of reference marked thereon.

Figure 1 of the drawings is a perspective view of my invention, showing it applied to one of the shafts of a vehicle; Fig. 2, a side elevation thereof; Fig. 3, a top plan view, and Fig. 4 a detail view in perspective.

The present invention has for its object to provide a simple and practically-operating device to be attached to a vehicle, whereby the horse can be readily and quickly disconnected from a vehicle should the horse start to run away, thereby preventing the animal taking the vehicle with him.

The invention consists in the details of construction, substantially as shown in the drawings, and hereinafter described and claimed.

In the accompanying drawings, A represents one of the shafts of a vehicle, and a 30 the usual cross-bar to which the two shafts are connected, and to which the singletree B is attached in the ordinary manner. A suitable frame, C, is attached to the upper side of each of the shafts of the vehicle by means of screws b, passing through elongated slots c and entering the shafts, as shown, whereby the frame will slide longitudinally on the shaft, as will be hereinafter described.

The ends of the singletree B are connected 40 to the frames, as hereinbefore described, by means of short straps c or other suitable devices.

The frames C are counterparts, and as one only is shown in the drawings, reference will 45 be made thereto, leaving it to be understood that two are in use to complete the device.

To the inner side of the frame C is pivoted a latch, D, provided upon under side with a spring, d, which bears upon a head, e, formed

with or secured to the frame C. A releasing 50 device, E, is provided to operate the latch D, said latch sliding on a guide-rod, f, secured to the side of the frame, and is beveled at its front end, as shown at g, so that when the device is forced forward by the spring h the end 55 will readily pass under the shank i of the latch to force it to its normal position. The releasing device E is supported in part by means of a short track, l, and the spring is preferably of the spiral form and coiled around the 60 guide-rod f, said releasing device having one end of a rope, strap, or cord, k, attached, and the other end extending into the vehicle within convenient reach of the driver or occupants. The head e has an open slot at its front end, 65 as shown at m, Fig. 3, and within this slot is located a headed dog, F, to which the traces are connected in any suitable manner, the traces being in two sections, n o, as shown.

In operation, should the horse become frightened and attempt to run away, by pulling on the cord k the device E is drawn back, which releases the latch D, and, as the latch is thus released, the spring d will force the front end up, as shown in Fig. 2, thus releasing the dog 75 F and with it the traces.

It is not necessary that the traces should be made in sections, and the dog therefore can be connected directly to the rear end of the trace.

Having now fully described my invention, what I claim as new, and desire to secure by Letters Patent, is—

The frame C, having pivoted latch D and spring d, in combination with the releasing 85 device E, spring h, guide-rod f, and cord k, and the open slotted head e and headed dog F, connected to the traces, and operating substantially as and for the purpose set forth.

In testimony that I claim the above I have 90 hereunto subscribed my name in the presence of two witnesses.

SIMEON A. PUGH.
